UNITED STATES PATENT OFFICE.

HUBERT S. TURNER, OF SAN DIEGO, CALIFORNIA.

SERVICE-METER SYSTEM FOR TELEPHONE-EXCHANGES.

1,147,347.

Specification of Letters Patent. Patented July 20, 1915.

Original application filed June 20, 1914, Serial No. 846,228. Divided and this application filed December 19, 1914. Serial No. 878,143.

To all whom it may concern:

Be it known that I, HUBERT S. TURNER, a citizen of the United States, residing at San Diego, in the county of San Diego and State of California; have invented certain new and useful Improvements in Service-Meter Systems for Telephone-Exchanges, of which the following is a specification.

This invention relates to a measured service system for telephone lines, whereby the calls initiated at a sub-station and obtaining a response at a called sub-station are automatically recorded by a service meter individual to the line of the calling sub-station.

15 The system constituting the subject of this application, is shown and described in an application for Letters Patent of the United States for telephone systems filed by me June 20, 1914, Serial No. 846,228, of which application the present one constitutes a division.

While the system is especially adapted for use with telephone systems of the common battery type having three conductor multiple jacks at the central office, it can readily be adapted to other systems.

In systems of this class it has been the practice to place a service meter for recording the calls from a sub-station line in series 30 or in multiple relation with the winding of the cut-off relay, used to extinguish the call initiating line signal, and to actuate the service meter by impressing a voltage upon the circuit greater than that used for the actuation 35 of the cut-off relay. This marginal action of the service meter has been found objectionable in many ways.

One of the objects of my present invention is to overcome these defects and I accomplish this in the specific way here shown 40 by impressing upon the circuit comprising the cut-off relay and service meter in multiple relation therewith a voltage preferably less than that necessary to actuate the cut-off relay. At the same time providing means whereby the current which actuates the cut-off relay cannot find a path through the operating winding of the service meter. Another defect in service meter systems, where- 45 in the meters are operated automatically when the called sub-station responds to its calling signal, is that if the calling subscriber has hung up his receiver previous to the response of the called subscriber and the 55 latter should respond previous to the taking

down of the connection by the switchboard operator, the call will still be registered on the calling subscriber's service meter, notwithstanding the fact that the call has not been completed. In my system this defect is 60 overcome.

Another object of the invention is the provision of means whereby a service meter for recording the total number of calls attended to by a switchboard operator is made a part 65 of the equipment individual to each operator's position, it being impossible to make said service meter record unless a connection is made to a sub-station line actually initiating a call, impossible to make it record but 70 one for each such connection made and impossible to make it record if a connection is made to a busy line. The object in so arranging the operation of the operator's service meter is to obtain a *bona fide* record of 75 the calls attended to by each operator. In other systems the operator can cause her service meter to record without actually having made a connection to sub-station lines initiating calls, or can make it record by 80 a connection to a busy line.

In order to more fully describe my invention, reference will now be had to the accompanying drawing forming a part of this specification and illustrating one specific embodiment of my said invention diagrammatically.

I have shown at A B, two telephone sub-stations, each including a telephone receiver a^1 , a transmitter a^2 , a switch-hook a^3 , a call bell a^4 , a condenser a^5 , and primary a^6 and secondary a^7 of an induction coil. The elements a^2 and a^6 being included in a bridge 90 of the telephone line, which bridge is open when the telephone receiver is upon the 95 switch-hook a^3 and which bridge is closed by the switch-hook a^3 , when relieved of the weight of the telephone receiver. The elements a^4 and a^5 , are included in another bridge permanently continuous with respect 100 to alternating currents, but non-continuous with respect to direct currents. The type of sub-station outfit shown is one that I have selected for the purpose of illustrating the invention, but it is to be understood that I 105 do not limit myself to the form of sub-station apparatus shown, for it will be seen as the description of the invention is proceeded with, that the operation of the system does not depend upon the peculiar sub-station 110

outfit shown. The sub-stations A and B are connected to the exchange in the form of the invention shown by means of metallic circuits, whose limbs C D and C¹ D¹ are connected with the line springs or talking contacts of spring jacks E, E¹ and F, F¹. A plurality of spring jacks is shown in multiple relation with each line, the lowermost spring jack F and F¹ constituting the answering jacks, while the remaining jacks E and E¹ constitute multiple jacks. The limbs C and D also terminate in contacts on the right and left hand armature switches of cut-off relay G, the limbs of each telephone line being normally connected by means of said armature switches and the contacts normally engaged thereby with a line relay H, the limb C being connected with the left hand winding and the limb D being connected with the right hand winding of said relay, the other terminals of the windings of said relay being connected through grounded battery K. Line relay H is actuated by the removal of the telephone receiver at sub-station A from its supporting switch-hook by means of a circuit which may be traced from transmitter a², through line C, left hand armature switch and normal contact of cut-off relay G, left hand winding of line relay H to the live pole of grounded battery K, through said battery to ground, through the right hand winding of line relay H, right hand normal contact and armature switch of cut-off relay G, line D, primary a⁶, switch-hook a³, completing the circuit through transmitter a². This actuation of line relay H causes its armature switch to close a circuit through line lamp or signal h¹ which may be traced from ground through said armature switch and engaged contact, said line lamp or signal, grounded battery K to ground, thus completing the circuit. Having observed the line signal of the calling sub-station the operator inserts plug N into the answering jack F, corresponding to the calling sub-station, and grasps the calling plug N¹ with finger contact device m¹. This finger contact device consists of an open ring of some suitable spring metal lined with an insulating substance to prevent contact of the metal portion thereof with the finger on which it is worn. A circuit can be traced from the live pole of grounded battery K through said device m¹, metallic thimble n¹ of calling plug N¹ in juxtaposition with it, normal contact of the middle armature switch of the three top ones of calling relay O, winding of operating relay P, sleeve contact of answering plug N, thimble of answering jack F, left hand winding of sub-station service meter V, winding of cut-off relay G to ground, thus completing the circuit through grounded battery K. The armature of the operating electro-magnet of sub-station serv-

ice meter V is not attracted by any current that can flow through its left hand winding, but said armature is maintained attracted thereby when current flowing through the right hand winding of said electro-magnet has caused the attraction of said armature. Therefore, the left hand winding constitutes a locking winding and the right hand winding an operating winding for said electro-magnet. 75

Both sub-station service meter V and operator's service meter W consist of an electro-magnet and an armature therefor, a train of counting wheels actuated or controlled by an escapement or other suitable device moved by the armature, and a spring switch adapted to open its contact after said meter has performed its recording function. The mechanical parts of this service meter are, however, well known in the art and need not here be shown and described in detail. In the drawing I have shown such meter diagrammatically. In my said application the circuit of finger contact device m¹ is shown as also energizing certain other relays, but as these constitute no part of my present invention they have been omitted from the drawing. It should also be noted that for the purpose of clearness in the drawing I have omitted various circuits and apparatus connected with the operator's telephone set and other circuits and apparatus not directly associated with my present invention. 85

The actuation of operating relay P, due to the circuit traced through its winding, allows current from the live pole of grounded battery K to flow through the winding of waiting relay R, the lowermost of the three top armature switches of operating relay P and the engaged contact thereof, 100 normal contact and spring switch r¹ of waiting relay R, normal contact and spring switch s¹ of answering relay S, winding of answering supervisory relay T, tip of answering plug N, tip spring of answering jack F, limb D, primary a⁶, switch-hook a³, transmitter a², limb C, ring spring of answering jack F, ring contact n² of answering plug N, spring switch s² and its normal contact of answering relay S, the engaged contacts of the uppermost of the three top armature switches of actuated operating relay P, 110 the right hand winding of split repeating coil U to ground, thus completing the circuit through grounded battery K. 115

The actuation of supervisory relay T, due to the current flowing through the circuit just traced, closes another circuit which may be traced from ground through the winding of cut-off relay G, left hand winding of sub-station service meter V, thimble of answering jack F, sleeve contact of answering plug N, alternate contact and armature switch of actuated supervisory relay T to the winding of answering relay S where the current di- 125 130

vides, a portion passing through said winding and supervisory lamp or signal t^1 to grounded battery K and a portion passing through the lowermost of the two top armature switches of answering relay S and its normal contact, the middle one of the three top armature switches of actuated operating relay P and its engaged contact, the winding of operator's service meter W, spring switch w^1 and its contact of the same meter to grounded battery K, completing the circuit through the same. The operation of answering relay S is prevented as long as the winding of the electro-magnet of operator's service meter W remains bridged across its winding as described, but the operation of said meter is allowed by the current that flows through said winding. Therefore, said electro-magnet attracts its armature, first operating the recording mechanism and then breaking the circuit through said winding by disengaging spring switch w^1 from its contact. The bridged circuit across the winding of answering relay S being thus removed, the latter at once actuates, thereby breaking the connection to the winding of operator's service meter W when the lowermost of the two top armature switches of said relay disengages its normal contact. Therefore, when spring switch w^1 of operator's service meter W reengages its contact, due to the cutting off of current from said winding when said spring switch disengaged its contact, current cannot pass through its winding again to energize said electro-magnet. Therefore, its mechanism cannot record more than once for every call the operator answers and cannot be made to record when there is no sub-station initiating a call on the line with which an answering plug may be connected, as in that case there would be no path for the current necessary to actuate supervisory relay T.

The actuation of answering relay S causes the uppermost of its two top armature switches to engage spring switch s^2 before disengaging the latter from its normal contact, in this way current from the left hand winding of split repeating coil U replaces the current from the right hand winding of the same, without breaking the connection to ground. At the same time the lowermost of its two bottom armature switches engages spring switch s^1 before the latter disengages its normal contact, in this way current from the left hand winding of split repeating coil U^1 replaces the current from the winding of waiting relay R, without breaking the connection to the live pole of grounded battery K.

So far as has been described, the circuit through substation A is now connected through supervisory relay T and the left hand windings of split repeating coil U and U^1 to the two poles of grounded battery K.

Operator's telephone receiver m^4 is bridged across the right hand windings of said repeating coil simultaneously with the operations hereinbefore described which connected sub-station A to the left hand windings of the same. Said connection being brought about when the uppermost of the three top and the uppermost of the three bottom armature switches of operating relay P engaged their respective contacts. Having obtained from the calling party at sub-station A the information that a connection is desired with sub-station B, for instance, the operator, still grasping the thimble n^1 of calling plug N^1 in such a way that finger contact device m^7 is in electrical contact with it, tests the line called for by touching the thimble of one of its multiple jacks with the tip of the plug, in a manner well known in the art. If the line tests "not busy," the calling plug N^1 is inserted in the multiple jack and a circuit is established which may be traced from the grounded terminal of cut-off relay G^1 , the winding of said relay, thimble of multiple jack E^1 , sleeve n^3 of calling plug N^1 , spring switch o^1 and its normal contact of calling relay O, winding of ringing relay Y, uppermost of the two bottom armature switches and its engaged alternate contact of actuated answering relay S, spring switch r^1 and its normal contact of waiting relay R, contact and lowermost of the three top armature switches of actuated operating relay P, winding of waiting relay R to the live pole of grounded battery K. The current flowing through this circuit is sufficient to actuate the three relays whose windings are traversed by the same. Ringing relay Y in pulling up its armature switches short-circuits the winding of waiting relay R, by means of a circuit which may be traced from the live pole of grounded battery K through the lowermost of the two top armature switches of said ringing relay Y and its engaged contact, the engaged contact and lowermost of the three top armature switches of actuated operating relay P to the upper terminal of the winding of waiting relay R. When waiting relay R releases its armature switches, due to this short-circuit, the current flowing through the winding of ringing relay Y and spring switch r^1 of waiting relay R passes to the live pole of grounded battery K through said lowermost armature switch of the two top ones of ringing relay Y and its engaged contact. The actuation of cut-off relay G^1 removes line relay H^1 in the same manner as described in relation to the removal of line relay H. Therefore, the display of line lamp or signal h^3 is prevented when the party at sub-station B removes the telephone receiver from its switch-hook. The exchange line apparatus associated with the line of sub-station B is shown without a

service meter, such as shown at V, as lines may be connected together which may or may not have such service meters associated with their line apparatus. The actuation of ringing relay Y also closes a circuit which may be traced from ground through ringing generator I¹, continuous ringing commutator K¹, engaged contact and lowermost of the three bottom armature switches of actuated operating relay P, normal contact and bottom armature switch of the short-circuited waiting relay R, alternate contact and uppermost one of the two bottom armature switches of actuated ringing relay Y, non-inductive resistance t³, tip of plug N¹, tip spring of multiple jack E¹, limb C¹ of the line of sub-station B, call bell or annunciator a⁴, condenser a⁵, limb D¹, ring spring of multiple jack E¹, ring contact n⁴ of calling plug N¹, uppermost contact and armature switch of the two top ones of actuated ringing relay Y, right hand winding of split repeating coil U, completing the circuit to ground. In this way an alternating current is impressed upon the call bell or annunciator a⁴, the operation of the same furnishing a calling signal for sub-station B.

When the party at sub-station B answers by removing his receiver from its switch-hook, limbs C¹ and D¹ are connected together as described in relation to sub-station A. The bell or annunciator a⁴ and condenser a⁵, before the removal of said receiver, allowed the passage of alternating currents only through said limbs, but now the passage of direct currents are allowed as well and on this account a new circuit is now closed which may be traced from the live pole of grounded battery K, through commutator M¹ and its brush, lowermost one of the two bottom armature switches of actuated ringing relay Y, switch spring y¹, winding of supervisory relay T², tip of calling plug N¹, tip spring of multiple jack E¹, limb C¹, primary a⁶, switch-hook a³, transmitter a², limb D¹, ring spring of multiple jack E¹, ring contact n⁴ of calling plug N¹, contact and uppermost armature switch of the two top ones of actuated ringing relay Y, right hand winding of split repeating coil U, completing the circuit through grounded battery K. Supervisory relay T² is actuated by the current flowing through the described circuit and its armature switch closes a circuit which may be traced from the live pole of grounded battery K, calling supervisory lamp or signal t⁴, winding of calling relay O, armature switch and alternate contact of calling supervisory relay T², sleeve n³ of calling plug N¹, thimble of multiple jack E¹, winding of cut-off relay G¹ to ground, completing the circuit through grounded battery K. The current flowing through this circuit causes the actuation of calling relay O and its bottom armature

switch engages spring switch o², which in turn causes spring switch o¹ to break its contact opening the circuit through the winding of ringing relay Y and thereby causing the latter to release its various armature switches, the engagement of the uppermost one of the two bottom armature switches with its normal contact and the engagement of spring switch y¹ with its normal contact bridging non-inductive resistance t³ across the winding of calling supervisory relay T². The lowermost armature switch of the two bottom ones of ringing relay Y has at the same time disconnected the live pole of grounded battery K, through commutator M¹ and its brush, from the winding of calling supervisory relay T², but before it did so, current from said pole through the right hand winding of split repeating coil U¹ was substituted for it; said current flowing through contact and bottom armature switch of calling relay O to normal contact of spring switch y¹, where it makes contact with the latter before the same is separated from its armature switch. Simultaneously with the engagement of its contact by the bottom armature switch of calling relay O, the uppermost of the three top armature switches of the latter engages its contact, thus substituting another connection to the ring contact n⁴ of calling plug N¹ from the right hand winding of split repeating coil U, before the same is broken by the corresponding armature switch of ringing relay Y. In this way, the current flowing through the winding of calling supervisory relay T² is uninterrupted notwithstanding its current connections have been changed and as the tip and ring strands of the link connector connected to calling plug N¹ are now connected to the right hand windings of split repeating coil U and U¹, conversation between sub-stations A and B is now possible.

The engagement of the lowermost one of the three top armature switches of calling relay O with its contact, closes a circuit which may be traced from said contact through battery X, which is preferably of a very low voltage, inner right hand armature switch and contact of actuated cut-off relay G, right hand winding of sub-station service meter V, spring switch v¹ of said meter and its contact, thimble of answering jack F, sleeve of answering plug N, contact and engaged armature switch of answering supervisory relay T, lowermost one of the two top armature switches of actuated answering relay S and its engaged alternate contact, lowermost one of the three top armature switches of actuated calling relay O, completing the circuit with the engaged contact of the same. The right hand winding of sub-station service meter V is such that on being so energized, it pulls up its ar- 125 130 135 140 145 150 155 160 165 170 175 180 185 190 195 200 205 210 215 220 225 230 ture, thereby, first operating its recording mechanism and then breaking the circuit through said winding by disengaging spring switch v^1 from its contact. In this manner, 5 battery X is removed from the circuit, as the current flowing through the left hand winding of service meter V (as hereinbefore explained) is sufficient to maintain the attraction of said armature though not sufficient to attract the same, therefore, its armature does not fall back and spring switch v^1 10 remains disengaged from its contact as long as cut-off relay G remains actuated. In this way I provide means for actuating service meters without increasing the voltage of 15 the current impressed on the circuit including the cut-off relay, notwithstanding said service meter is in multiple relation to said relay. The only object in breaking the circuit from battery X at the innermost right hand armature switch of cut-off relay G, is to prevent current from battery K which passes through the thimbles of answering jack F to ground through the left hand 20 winding of service meter V and winding of cut-off relay G, from being shunted through the right hand winding of said meter, the right hand windings of corresponding service meters associated with idle sub-station 25 lines and thence to ground through the windings of the cut-off relays associated with those lines. By breaking the circuit through said right hand winding at said cut-off relay armature switch, there is no such shunt circuit available, as the only path for such a 30 shunt would be through the described windings associated with busy lines, as exemplified by engaged contacts with armature switches of said cut-off relays, in which case 35 no current would flow through the right hand winding of service meter V, as said winding would form part of a bridge between circuits having the same resistance. The principle involved being the same as 40 that used in a Wheatstone bridge, said right hand windings being connected in a way corresponding to the galvanometer usually 45 used with said Wheatstone bridge.

Previous to the actuation of calling relay 50 O and the consequent closure of the circuit through the right hand winding of service meter V, a circuit through the latter might have been traced from ground through the winding of cut-off relay G, left hand winding 55 of service meter V, contact and armature switch v^1 of the same and its right hand winding, innermost right hand armature switch and contact of actuated cut-off relay G, battery X, contact and lowermost one of 60 the three top armature switches of actuated calling relay O associated with a link connector other than the one associated with the described service meter and cut-off relay circuit, lowermost of the two top armature 65 switches and alternate contact of actuated

answering relay S of said link connector, sleeve contact of plug N of said link connector, thimble contact of answering jack F, left hand winding of service meter V and winding of cut-off relay G associated with the same link connector, completing the circuit to ground. 70

A circuit in branch relation to the above circuit might have been traced from ground through battery K, supervisory lamp or signal t^1 , winding of answering relay S, armature switch and alternate contact of answering supervisory relay T, joining the circuit already traced at sleeve contact of answering plug N. Therefore, the resistance in 75 series with the right hand winding of any service meter V previous to the actuation of said meter, is that of these two circuits in multiple relation. In order to prevent the actuation of said service meter V by the current from battery X allowed to pass through its right hand winding by this means, said winding is of a very low resistance and the left hand winding of the same meter together with the winding of cut-off relay G, 80 is, in comparison, of a high resistance. The winding of answering relay S together with supervisory lamp or signal t^1 , is, in comparison, also of a high resistance, and battery X being of a voltage lower than that of 85 battery K, sufficient operating current for the right hand winding of service meter V is not allowed to pass by means of the circuits traced. In other words, service meter V is 90 only operable when calling relay O, of the 95 particular link connector associated with the line of the sub-station pertaining to said meter, closes the circuit already traced through battery X and the right hand winding of said meter and which circuit does not 100 include any additional resistance. Current from grounded battery K is also kept from flowing through battery X in series with the right hand winding of service meter V, as when such a path is available by the actuation of calling relay O of one engaged link connector and the non-actuation of said relay of another engaged link connector, battery X in series with said winding is bridged 105 across circuits having the same resistance. 110 Therefore, the well known Wheatstone bridge circuit is again involved and no current flows through said winding. While I do not claim as new, the use of the Wheatstone bridge principle, I do claim as new its 115 application in the operation of a service meter, as described.

Battery X and the lines connecting the same to the innermost right hand contact of cut-off relay G and contact of the lowermost 120 one of the three top armature switches of calling relay O, may be common to the entire exchange or common only to groups of said cut-off relays and groups of link connectors, such as that shown in the drawings. 125 130

When the connected sub-stations A and B have completed their conversations and have replaced their respective telephone receivers upon their switch-hooks, the armature of the 5 controlling electro-magnet of service meter V is released and said meter is placed in position to record again. Should the party at substation B replace the receiver on its switch-hook first; then the circuit for direct 10 current is at once broken through primary a^6 and switch-hook a^3 . Therefore, calling supervisory relay T² releases its armature switch, breaking the circuit through the winding of calling relay O, the armature 15 switches of the same thereupon resuming their normal condition, opening all the circuits through the tip, ring and sleeve contacts of calling plug N¹. Due to the opening of the circuit through sleeve contact n^3 20 of calling plug N¹, cut-off relay G¹ is de-energized, thereby releasing its armature switches which upon engaging their contacts connect line relay H¹ to the limbs C¹ and D¹ of the line of sub-station B, so that 25 line signal h³ will again respond on the removal of telephone receiver a^1 from its switch-hook. When the party at sub-station A replaces the receiver upon its switch-hook, the circuit for direct current is broken, 30 as hereinbefore described in relation to sub-station B, the de-energization of answering supervisory relay T breaking the circuit through the winding of answering relay S, the armature switches of the same there- 35 upon resuming their normal condition and opening all the circuits through the tip, ring and sleeve contacts of answering plug N. Due to the opening of the circuit through the sleeve contact of said plug, cut-off relay 40 G is de-energized and consequently the left hand winding of service meter V, the release of the armature of the controlling magnet of the same allowing spring switch v¹ to re-engage its contact, thereby placing said 45 meter in an operable condition. Line relay H and line lamp or signal h¹ is restored to the control of sub-station A in the same manner as described in relation to sub-sta- 50 tion B.

It will be observed that means are provided whereby if the calling party replaces the receiver of sub-station A upon its switch-hook previous to the response of the called sub-station B, the consequent deener- 55 gization of answering relay S would cause the de-energization of ringing relay Y by opening the circuit through the winding of the same when the uppermost of the two bottom armature switches of said answering 60 relay S disengages its contact. Said deenergization of ringing relay Y and the consequent release of its armature switches not only prevents the ringing of the called sub-station's call bell, but prevents the actuation 65 of calling relay O should the called sub-sta-

tion respond, as the circuit through limbs C¹ and D¹ is opened by said deenergization of ringing relay Y. Therefore, should the calling party replace his receiver upon its switch-hook previous to the response of the 70 called sub-station, thereby abandoning the call he has initiated, the service meter associated with said calling party's line will not register the call should the called party subsequently respond. 75

When answering plug N is inserted in a spring jack and the thimble n^1 of calling plug N¹ is grasped by finger contact device m^1 , a circuit has been traced from ground through cut-off relay G and service meter 80 V, thimble of answering jack F, winding of operating relay P, thimble n^1 of calling plug N¹, finger contact device m^1 to the live pole of grounded battery K. The current so derived is sufficient to energize the winding of 85 operating relay P and cause same to pull up its various armature switches; however, if there is another plug, either answering or calling, inserted in a spring jack multiplied on the same line, and if current from battery 90 K is passing through the same, then the di- 95 vided current at the thimbles of the spring jacks is not sufficient to so energize said winding of operating relay P. As the circuit through the winding of operator's serv- 100 ice meter W is closed by the engagement of the middle one of the three top armature switches of operating relay P, it will be seen that said meter will not record if a connection is made to a busy line. 105

Instead of energizing operating relay P by means of the described finger contact de- 110 vice, the line leading to thimble n^1 of calling plug N¹ could be connected to one contact of a key or button, the live pole of grounded 115 battery K being connected to the other contact of the same, thus substituting a man- 120 ually operated key or button for the de- 125 scribed finger contact device.

While I have shown and described my in- 110 vention with respect to certain details and combinations it is to be understood that I do not wish to limit myself thereto, many de- 115 viations and modifications being possible without in any way departing from the 120 spirit and scope of my invention. 125

What I claim is:—

1. In a system of the class described, a Wheatstone bridge circuit, a service meter individual to each of a plurality of sub-sta- 120 tion lines and having a winding connected in the bridge wire of said circuit, and means to energize said winding to cause said meter to record.

2. In a system of the class described, a Wheatstone bridge circuit, a service meter having a winding connected in the bridge wire, across the arms of said circuit and another winding forming a part of an arm of said circuit and means to energize said 130

first mentioned winding to operate said meter.

3. In a system of the class described, a Wheatstone bridge circuit, a service meter having a winding balanced across the arms of said circuit, and means to energize said winding to operate said meter, by unbalancing said Wheatstone bridge circuit without altering the resistance of said arms.

10 4. In a system of the class described, a Wheatstone bridge circuit, a source of electricity to energize the same, a service meter having a winding balanced across the arms of said circuit, and means including a separate source of electricity to impress current upon said winding to energize the same.

15 5. A telephone exchange system, including telephone lines extending from sub-stations to an exchange, connecting apparatus and link connectors for connecting said sub-stations, a cut-off relay, a service meter associated with a sub-station line, an electro-magnet for operating said meter and comprising an operating winding and a locking winding in branch relation to said operating winding and in series with the winding of said cut-off relay, automatic means to render said meter inoperative when the line associated therewith is a called line, and automatic means including said connecting apparatus to render the same operative when said line is a calling line and the called sub-station connected thereto has responded to its calling signal.

20 6. A telephone exchange system, including telephone lines extending from sub-stations to an exchange, connecting apparatus and link connectors for connecting said sub-stations, a cut-off relay, a service meter associated with a sub-station line, an electro-magnet for operating said meter and comprising an operating winding and a locking winding in branch relation to said operating winding and in series with the winding of said cut-off relay, automatic means to render said meter inoperative when the line associated therewith is a called line, automatic means including said connecting apparatus to render the same operative when said line

25 is a calling line and the called sub-station connected thereto has responded to its calling signal, and means under the control of apparatus at the calling sub-station previous to the response of the called sub-station, whereby said meter is rendered inoperative by the subsequent response of said called sub-station.

30 7. A telephone exchange system, including telephone lines extending from sub-stations to an exchange, connecting apparatus and link connectors for connecting said sub-stations, a cut-off relay, a service meter associated with a sub-station line, an electro-magnet for operating said meter and comprising an operating winding and a locking

winding in branch relation to said operating winding and in series with the winding of said cut-off relay, and means whereby current to actuate said cut-off relay is prevented from flowing through said operating winding.

75 8. A telephone exchange system, including telephone lines extending from sub-stations to an exchange, connecting apparatus and link connectors for connecting said sub-stations, a cut-off relay, a service meter associated with a sub-station line, an electro-magnet for operating said meter and comprising an operating winding and a locking winding in branch relation to said operating winding and in series with the winding of said cut-off relay, means whereby current to actuate said cut-off relay is prevented from flowing through said operating winding, and means under the control of apparatus at a called sub-station to impress operating current on said operating winding of said meter when the same is associated with the line of a calling sub-station which is connected to said called sub-station.

80 9. A telephone exchange system, including telephone lines extending from sub-stations to an exchange, connecting apparatus and link connectors for connecting said sub-stations, a cut-off relay, a service meter associated with a sub-station line, an electro-magnet for operating said meter and comprising an operating winding and a locking winding in branch relation to said operating winding and in series with the winding of said cut-off relay, means whereby current to actuate said cut-off relay is prevented from flowing through said operating winding, and means under the control of apparatus at a called sub-station to impress operating current on said operating winding of said meter when the same is associated with the line of a calling sub-station which is connected to said called sub-station, and means under the control of apparatus at said calling sub-station and operative previous to the aforesaid called sub-station means to prevent the impression of said operating current on said operating winding.

85 10. A telephone exchange system, including telephone lines extending from sub-stations to an exchange having line signaling apparatus for said telephone lines, connecting apparatus and link connectors for connecting said sub-stations, a service meter associated with a sub-station line and having a controlling electro-magnet provided with a locking and an operating winding, a cut-off relay for controlling said line signaling apparatus governed by said connecting apparatus and in series with said locking winding, said operating winding being in branch relation to said locking winding, the actuation of said cut-off relay closing a circuit through said operating winding and

connecting the same to a limb of a circuit common to a plurality of said meters, said operating winding being thereby included in a bridge across circuits having the same resistance, whereby current from said connecting apparatus to actuate said cut-off relay is prevented from being shunted through said operating winding.

11. A telephone exchange system, including telephone lines extending from sub-stations to an exchange having line signaling apparatus for said telephone lines, connecting apparatus and link connectors for connecting said sub-stations, a source of electricity, a service meter associated with a sub-station line and having a controlling electro-magnet provided with a locking and an operating winding, a cut-off relay for controlling said line signaling apparatus governed by said connecting apparatus and in series with said locking winding, said operating winding being in branch relation to said locking winding, the actuation of said cut-off relay closing a circuit through said operating winding and connecting the same to a limb of a circuit common to a plurality of said meters, said operating winding being thereby included in a bridge across circuits having the same resistance, whereby current from said connecting apparatus to actuate said cut-off relay is prevented from being shunted through said operating winding, and means under the control of apparatus at a called sub-station to connect said limb through said source of electricity to said windings in branch relation to each other, thereby causing the operation of said service meter by current from said source flowing through said operating winding.

12. A telephone exchange system, including telephone lines extending from sub-stations to an exchange having line signaling apparatus for said telephone lines, connecting apparatus and link connectors for connecting said sub-stations, a source of electricity, a service meter associated with a sub-station line and having a controlling electro-magnet provided with a locking and 45 an operating winding, a cut-off relay for controlling said line signaling apparatus governed by said connecting apparatus and in series with said locking winding, said 50 operating winding being in branch relation to said locking winding, the actuation of said cut-off relay closing a circuit through said operating winding and connecting the same to a limb of a circuit common to a plurality of said meters, said operating winding being included in a bridge across 55 circuits having the same resistance, whereby 60 current from said connecting apparatus to actuate said cut-off relay is prevented from being shunted through said operating winding, and means under the control of appa- 65

ratus at a called sub-station to connect said limb through said source of electricity to said windings in branch relation to each other, thereby causing the operation of said service meter by current from said source flowing through said operating winding, and means under the control of apparatus at the calling sub-station and operative previous to the aforesaid called sub-station means to prevent said connection to said windings by opening the circuit thereto, thereby preventing the operation of said service meter.

13. A telephone exchange system, including telephone lines extending from sub-stations to an exchange having line signaling apparatus for said telephone lines, connecting apparatus associated with link connectors for connecting said sub-stations, connecting means for said link connectors associated with said lines, a cut-off relay having its winding in a local circuit closed through a contact of said connecting means when one of said link connectors is engaged therewith, a service meter associated with a sub-station line, an electro-magnet for operating said meter, a winding on said electro-magnet one terminal of which is also connected to said contact of said connecting means the other terminal being connected to a limb of a circuit common to a plurality of said service meters by the actuation of said cut-off relay, said winding thereupon forming part of a bridge across circuits having the same resistance, whereby current from said connecting apparatus flowing through said link connector engaged with said contact to actuate said cut-off relay is prevented from being shunted through said winding. 80 85 90 95 100

14. A telephone exchange system, including telephone lines extending from sub-stations to an exchange having line signaling apparatus for said telephone lines, connecting apparatus associated with link connectors for connecting said sub-stations, connecting means for said link connectors associated with said lines, a source of electricity and a second source of electricity of higher voltage than the first mentioned source, a cut-off relay for controlling said line signaling apparatus and having its winding in a local circuit closed through a contact of said connecting means when one of said link connectors is engaged therewith, a service meter associated with a sub-station line, an electro-magnet for operating said meter, a winding on said electro-magnet one terminal of which is also connected to said contact of said connecting means the other terminal being connected to a limb of a circuit common to a plurality of said service meters by the actuation of said cut-off relay, said winding thereupon forming part of a bridge across circuits having the same resistance, whereby current from said connecting appa- 120 125 130

ratus and said second mentioned source of electricity flowing through said link connector engaged with said contact to actuate said cut-off relay is prevented from being shunted through said winding, and means under the control of apparatus at a called sub-station to connect said limb common to a plurality of said service meters through said first mentioned source of electricity to said 10 contact of said connecting means, thereby causing the operation of said service meter by current from said source flowing through said winding.

15. A telephone exchange system, including telephone lines extending from sub-stations to an exchange having line signaling apparatus for said telephone lines, connecting apparatus associated with link connectors for connecting said sub-stations, connecting means for said link connectors associated with said lines, a source of electricity and a second source of electricity of higher voltage than the first mentioned source, a cut-off relay for controlling said 20 line signaling apparatus and having its winding in a local circuit closed through a contact of said connecting means when one of said link connectors is engaged therewith, a service meter associated with a sub-station line, an electro-magnet for operating said meter, a winding on said electro-magnet one terminal of which is also connected to said contact of said connecting means the other terminal being connected to a limb of a circuit common to a plurality of said service meters by the actuation of said cut-off relay, said winding thereupon forming part of a bridge across circuits having the same resistance, whereby current from said connecting apparatus and said second mentioned source of electricity flowing through said link connector engaged with said contact to actuate said cut-off relay is prevented from being shunted through said winding, and means under the control of apparatus at a called sub-station to connect said limb common to a plurality of said service meters through said first mentioned source of electricity to said contact of said connecting means, thereby causing the operation of said service meter by current from said source flowing through said winding, and means under the control of apparatus at the calling sub-station and operative previous to the aforesaid called sub-station means to prevent the connection to said contact by opening the circuit thereto, thereby preventing the operation of said service meter.

16. A telephone exchange system, including telephone lines extending from sub-stations to an exchange having line signaling apparatus for said telephone lines, connecting apparatus associated with link connectors for connecting said sub-stations, a service meter associated with a sub-station line,

a cut-off relay governed by said connecting apparatus for controlling said line signaling apparatus and for closing a circuit through said service meter, said cut-off relay having its winding in a local circuit closed by 70 means of one of said link connectors when connected to a sub-station line, the actuating electro-magnet of said service meter having a locking winding included in the same local circuit and an operating winding in branch

75

relation to said locking winding but adapted to be energized by a current of lower voltage than that required to actuate said cut-off relay, and means whereby after the recording of a call on said service meter, its operating winding is permanently removed from said branch relation until the calling line link connector becomes idle.

80

17. A telephone exchange system, including telephone lines extending from sub-stations to an exchange having line signaling apparatus for said telephone lines, connecting apparatus associated with link connectors for connecting said sub-stations, a service meter associated with a sub-station line, 90 a cut-off relay governed by said connecting apparatus for controlling said line signaling apparatus and for closing a circuit through said service meter, said cut-off relay having its winding in a local circuit closed by means 95 of one of said link connectors when connected to a sub-station line, the actuating electro-magnet of said service meter having a locking winding included in the same local circuit and an operating winding in branch 100 relation to said locking winding, means whereby the current in said local circuit is prevented from passing through said operating winding to operate the same, said means including a connection from said operating winding to a limb of a circuit common to a plurality of said service meters, said connection being made only on the actuation of said cut-off relay, whereby said operating winding always forms part of a 110 bridge across circuits having the same resistance when so connected, and means whereby after the recording of a call on said meter, its operating winding is permanently removed from said branch relation until the 115 calling link connector becomes idle, said means including a spring switch associated with the mechanism of said meter which breaks the connection through said operating winding after the call has been registered, the current flowing through said locking winding thereupon maintaining said connection open.

105

18. A telephone exchange system, including telephone lines extending from sub-stations to an exchange having line signaling apparatus for said telephone lines, connecting apparatus associated with link connectors for connecting said sub-stations, a service meter associated with a sub-station line, 125 130

15 a cut-off relay governed by said connecting apparatus for controlling the line signaling apparatus and for closing a circuit through said meter, said cut-off relay having its winding in a local circuit closed when one of said link connectors is connected to a sub-station line, the actuating electro-magnet of said meter having a locking winding included in the same local circuit and an operating winding in branch relation to said locking winding but adapted to be energized by a current of lower voltage than that required to actuate said cut-off relay provided there is no other resistance in circuit, means 20 whereby the current of higher voltage in said local circuit is prevented from passing through said operating winding to operate the same, said means including a connection from said operating winding to a limb of a circuit common to a plurality of said meters, said connection being made only on the actuation of said cut-off relay, whereby said operating winding always forms part of a bridge across circuits having the same resistance when so connected, and means whereby after the recording of a call on said meter its operating winding is permanently removed during an established connection by one of said link connectors from said operative connection with said current of lower voltage, said means including a spring switch associated with the mechanism of said meter which breaks the connection through said operating winding after the 25 call has been registered, the current flowing through said locking winding thereupon maintaining said connection open.

19. A telephone exchange system, including telephone lines extending from sub-stations to an exchange, link connectors terminating in answering and calling plugs to connect said sub-stations, an answering relay and a calling relay associated with each of said link connectors, a cut-off relay, a service 40 meter associated with the exchange apparatus of a substation line and actuated by an electro-magnet only when said sub-station is a calling one and has been connected by one of said link connectors to a called sub-station that has responded to its calling signal, an operating winding on said electro-magnet, the operating circuit of which includes a source of electric energy, an armature switch and normally disengaged contact of said 45 calling relay, an armature switch and normally disengaged contact of said answering relay, sleeve contact of said answering plug, an armature switch and normally engaged contact of said electro-magnet and an armature switch and normally disengaged contact of said cut-off relay, said circuit being closed by the actuation of said calling relay, means under the control of apparatus at said calling sub-station to maintain the actuation 50 of said cut-off relay and said answering re-

lay, and means under the control of apparatus at said called sub-station to actuate said calling relay provided said answering relay is in its actuated condition, the energization of said operating winding causing 70 the operation of said service meter first and then the disengagement of said armature switch of said electro-magnet from its contact, thus opening the circuit through said operating winding, and a locking winding 75 on said electro-magnet in series with said cut-off relay to maintain said disengagement.

20. A telephone exchange system, including telephone lines extending from sub-stations to an exchange, apparatus at said sub-stations for signaling an operator at said exchange, link connectors to connect said sub-stations, a service meter common to a group of said link connectors for automatically recording the calls answered by an operator assigned to said group, an electro-magnet for operating said meter and an operating circuit therefor, operator controlled means for closing said circuit when one of said link connector's is connected to a calling line, means to render said meter inoperative to record a call unless said link connector is so connected, and means to render said meter inoperative, after having 80 recorded once, by the subsequent manipulation of said apparatus at a sub-station, until said operating circuit is again closed by said operator controlled means subsequent to said manipulation. 106

21. A telephone exchange system, including telephone lines extending from sub-stations to an exchange, apparatus at said sub-stations for signaling an operator at said exchange, link connectors to connect said sub-stations, a supervisory relay and an answering relay, a service meter common to a group of said link connectors for automatically recording the calls answered by an operator assigned to said group, an electro-magnet for operating said meter and an operating circuit therefor, operator controlled means for closing said circuit when one of said link connectors is connected to a calling line, means whereby the non-energization of said supervisory relay renders said meter inoperative to record a call unless said link connector is so connected, and means whereby the energization of said answering relay renders said meter inoperative to record more than once for each call answered by said operator. 108 110 115 120

22. A telephone exchange system, including telephone lines extending from sub-stations to an exchange, apparatus at said sub-stations for signaling an operator at said exchange, link connectors to connect said sub-stations, a service meter common to a group of said link connectors for automatically recording the calls answered by an op- 125 130

erator assigned to said group, means controlled by said operator for operating said meter, means to render said meter inoperative to record a call unless one of said link 5 connectors is first connected to a line whose sub-station is signaling, said means including an electro-magnet for operating said meter, a circuit including jack contacts associated with said sub-station lines and contacts 10 on answering plugs associated with said link connectors, for the transmission of current to the winding of said electro-magnet, a supervisory relay the actuation of which is essential for the closing of said circuit, said relay only actuating when a circuit 15 is closed at said sub-station, and means to render said meter inoperative, after having recorded once, by the subsequent manipulation of said apparatus at a sub-station, 20 until said means controlled by said operator is again employed.

23. A telephone exchange system, including telephone lines extending from sub-stations to a multiple switchboard, link connectors 25 terminating in answering and calling plugs to connect said sub-stations, a service meter for automatically recording the calls answered by an operator, and means to render said meter inoperative to record a call if one of said link connectors 30 is connected to a busy line.

24. A telephone exchange system, including telephone lines extending from sub-stations to a multiple switchboard, link connectors 35 terminating in answering and calling plugs to connect said sub-stations, a service meter for automatically recording the calls answered by an operator, and means to render said meter inoperative to record a call if one of said link connectors is connected to a busy line, said means including 40 an operating circuit for said meter, operator controlled means the actuation of which is essential to the completion of said circuit, said means being operative only by the full 45 force of the current which can pass through a local circuit associated with an idle line, said means being inoperative if said link connector is connected to a busy line.

25. A telephone exchange system, including telephone lines extending from sub-stations to an exchange, link connectors to connect said sub-stations, a service meter for automatically recording the calls answered 50 by an operator, and means to render said meter inoperative to record more than once for each call answered, said means including an electro-magnet and an operating circuit therefor to operate said meter, an answering

relay, and operator controlled means essential to establish a connection by one of said link connectors to bridge the winding of said electro-magnet across the winding of said answering relay to prevent the actuation of said relay, a spring switch adapted to open 60 the circuit through said electro-magnet, after said service meter has operated, to permit the actuation of said relay, and an armature switch associated with said relay to prevent the closing of said circuit of said electro-magnet during the actuation of said relay.

26. A telephone exchange system including telephone lines extending from sub-stations to an exchange, link connectors to connect said sub-stations, an operator's telephone set, a service meter for automatically recording the calls answered by an operator, and means to compel the operation of said meter before said operator's telephone set is telephonically connected to a line initiating 75 a call, and means controlled by said meter on the completion of its operation in registering a call to automatically connect said operator's telephone set to said line.

27. A telephone exchange system, including telephone lines extending from sub-stations to an exchange, link connectors to connect said sub-stations, an operator's telephone set, a service meter for automatically recording the calls answered by an operator, 80 and means to compel the operation of said meter before said operator's set is telephonically connected to a line initiating a call, and means controlled by said meter on the completion of its operation in recording a 85 call to automatically connect said operator's telephone set to said line, said means including an electro-magnet and an operating circuit therefor to operate said meter, an answering relay, and operator controlled means 90 essential to establish a connection by one of said link connectors to bridge the winding of said electro-magnet around the winding of said answering relay to prevent the actuation of said relay, a spring switch adapted 95 to open the circuit through said electro-magnet, after the service meter has operated, to permit the actuation of said relay, and a circuit closed by the actuation of said relay to telephonically connect said operator's telephone set to said line initiating a call.

In testimony whereof I affix my signature in presence of two witnesses.
